PISTON AND CYLINDER CONSTRUCTION

Frazer W. Gay, Metuchen, N. J.

Original application September 1, 1942, Serial No. 456,909. Divided and this application April 16, 1943, Serial No. 483,363.

6 Claims. (Cl. 309—2)

This invention relates to an earth imbedded pumping engine, piston and cylinder construction, being a modification of the pump shown in my U. S. Patent No. 1,846,389, dated February 23, 1932, and this application is a division of my pending application Ser. No. 456,909, filed September 1, 1942.

This invention relates to a novel piston and cylinder construction employing the strength of the earth to support the lateral pressure on the cylinder walls, and employing the weight of a heavy concrete structure to withstand the upward pressure of the gases within the cylinder.

The cylinder walls comprise flat sides, whereby there are no resultant forces acting to open cracks in the cylinder walls, except at the angles between the flat sides.

U. S. patent application Serial No. 456,909, explains in detail the method employed in sealing the cracks against the leakage of gas and water.

In a preferred type of cylinder covered by the present invention the hot gases are expanded to or nearly to atmospheric pressure, and, for the type of engine according to this invention, the cylinder must be set relatively close to the earth's surface if the cylinder volume is to be employed efficiently. The use of a heavily weighted stopper employing a large mass of concrete and rock to overcome the upward gas pressure constitutes an economic method of providing a cylinder head.

It is an object of the present invention to provide an earth imbedded engine cylinder with a plurality of flat walls; each wall comprising a concrete mass arranged to carry the lateral fluid pressure from the wall to the earth surface, whereby the unit stress on the earth is relatively low. Conduits formed in said concrete mass act to conduct water to said cylinder.

It is a further object of the present invention to support the enormous gas pressure against the top or head of the cylinder by a concrete and steel stopper, said stopper resisting the enormous upward pressure of the burning gases by the greater downward pressure of its very great weight.

It is a further object to utilize a very strong structure of concrete and steel to constitute a stopper to oppose the upward pressure of the cylinder gases, and to supply the necessary additional weight by loading this structure with a mixture of sand, rock, gravel or like weighty material.

It is a further object of this invention to provide a float on water within the cylinder, which float constitutes the top of the liquid piston

formed by said water, and to face the floor of the float with fire brick, or other suitable heat insulator, and to line that portion of the cylinder walls exposed to hot gases with special heat insulating material, so that as the piston rises and falls, cool surfaces are not continuously exposed so as to continuously absorb radiant heat from the contained gases, and from the hot piston float and roof of the large gas-filled chamber of the cylinder.

Other objects of this invention not at this time more particularly enumerated will be clearly understood from the following description of same. The invention is clearly illustrated in the accompanying drawings, in which—

Fig. 1 is an elevation in section of the pump of the present invention.

Fig. 2 is a plan view of Fig. 1.

Fig. 3 is an enlarged cross section of the engine cylinder and valve shown in Fig. 1.

Fig. 4 is a cross section in plan marked AA in Fig. 3.

Fig. 5 is a sectional elevation of the valves and supporting structure along the lines BB in Fig. 2.

Fig. 6 is an elevation of the valve grid shown in Fig. 5.

Fig. 7 is a cross section of the play pipe 22 of Fig. 1.

Fig. 8 is an enlarged cross section of one of the seals shown in Fig. 6.

Fig. 8A is an enlarged cross section of two seal blocks similar to those shown in Fig. 7.

Fig. 9 is a cross section of one of the gas seals located in a corner position of the cylinder 13 of Fig. 3.

Fig. 10 shows a gas seal located around the top of combustion engine cylinder 13 in Fig. 3 and is represented by the number 100 in Fig. 15.

Fig. 10A shows an extension joint and seal.

Fig. 11 is a device for maintaining the hydraulic pressure in the gas seals of Fig. 9 and Fig. 10 at all times above the pressure of the gas in the cylinder 13.

Fig. 12 is a cross section of the wall of cylinder 13 showing the arrangement of the heat-insulating curtains, which are arranged in the form of shingles.

Fig. 13 shows the arrangement of the hanger irons supporting the insulating curtain of Fig. 12.

Fig. 14 is an elevation of a shingle in the curtain shown in Fig. 12.

Fig. 15 is an enlarged section of the cylinder head plug 16 shown in Fig. 1.

Similar characters of reference are employed

in all of the above described views to indicate corresponding parts.

In Fig. 1 and in the accompanying plan view Fig. 2, the reference 1 indicates a dam in a river having overflow gates 2 so as to maintain a maximum elevation level E1. Reference number 3 represents a lighter structure dam built about the base of the main dam so as to form a reservoir and hold water up to the elevation E1 in the lake produced by the main dam 1. 4 represents buttresses on the dam. 5 indicates emergency overflow nozzles which are sealed closed by the stop logs 6. The tail water is shown at elevation 7 so that the normal head of the dam is 8. A portion 9 of a conical hole is carved out of the rock. This portion comprises approximately 200/360 parts of a complete cone. The engine cylinder chamber 13 has four flat walls 15, 15, 15, 15, constituting a rectangular cylinder (although a cylinder of any polygon shape would be satisfactory). The cylinder walls 15, 15, 15, 15 are cast integral with the reinforced masonry walls 10, 10, 10, 10, etc. These walls are cast directly against the bedrock 31. At the junction of each pair of walls, however, are left the cracks 30. These cracks are continuous from the cylinder back to the bedrock so that each of the four cylinder walls is cast independently and integrally with the bedrock. Between the vertical walls 10, 10, 10, etc., are the vertical passages 11, 11, 11, etc., down which the water flows from the tailrace to the high pressure valves 17. In the preferred form of the invention, the tops of the walls 10, 10, 10 are cut away as at 12 so as to allow a freer flow of water in passing around the cylinder to freely enter any of the passages 11, 11, 11. The high pressure valves 17 are shown located on the three sidewalls below cylinder walls 15. These valves 17 are supported by a grid. This grid comprises thin, rather deep vertical pieces of steel plate next the valves which in turn are imbedded in concrete horizontal beams 18. The low-pressure valves 19 are supported on a similar, but lighter structure carried by the supporting walls, 34, 34, 34, etc.

The high-pressure exit chamber opens out through the arched opening 20 into the conical guide reducer 21. Liquid flows from guide reducer 21 into and through the rectangular water conduit 22. A section of this rectangular water conduit 22 is shown in Fig. 7 along the lines CC of Fig. 1. While the drawings show a rectangular water conduit, it is to be understood that a play pipe having any polygon structure is satisfactory. The low-pressure end of the water conduit expands outwardly through the expanding elbow 23 through the valves 19 and through the large opening 24 into the reservoir bounded by the walls 3, 3, 3. Water pumped into this reservoir flows through the gates 2 into the lake above the dam 1.

In the preferred form of the invention, guide veins 25, 25 are placed on the outlet reservoir side of valves 2; and similar guide veins 26, 26 are placed in the reservoir structure. These guide veins serve to carry the water through the gates 2 at high velocity, but receive water at the flared ends of guide veins 25—25 at low velocity and discharge it at the flared ends of guide veins 26, 26, also at low velocity, whereby although there is considerable energy in this water when it passes through the gates 2, 2, etc., there is very little leaving energy in the water when it is discharged into the lake L.

It will be noted that the entire force on the cylinder walls, the valve chamber walls, the reducing chamber walls 21, and the water conduit walls 22 is taken by the rock structure of the earth leaving only the upward force at the cylinder head to be otherwise carried. I have shown this upward force carried by a cylinder head 16 comprising an enormous mass, or stopper, of concrete and gravel. The main structure of this stopper is reinforced concrete, but a great portion of the weight is made up of the filling which is preferably rock and gravel. This stopper 16 contains all the valve mechanisms and other mechanical devices common to internal combustion engines, and no novelty is claimed for these devices in this application.

The gases coming up the sides of the stopper 16 pass to the smokestack 133. A concrete bulkhead 25' is built to protect the stopper 16 against floods. On top of this bulkhead 25' is located the compressor house 26'. It is the function of the compressor house 26' to compress and deliver to the inlet valves in stopper 16 the necessary amount of compressed air to supply the cylinder chamber 13.

It is to be understood that in the preferred form of this invention, no fresh air is introduced into the cylinder chamber 13 at atmospheric pressure. All combustion air comes through the compressor 26'. Although it is to be understood that if it is desired, fresh air can be introduced into the chamber 13 through auxiliary valves and compressed by the inlet water flowing from the tailrace level into the cylinder chamber 13. I prefer to allow a portion of hot gases to remain in cylinder chamber 13 sufficient to be compressed to very nearly normal inlet pressure. The engine therefore operates on a cycle similar to that of a single acting steam engine as far as inlet gases are concerned, given a working stroke for every complete piston cycle.

Fig. 3 is an enlarged section of the cylinder of Fig. 1. This figure shows the stopper 16 having a portion projecting several feet downwards into the cylinder chamber 13. The clearance between the projections 29 on the stopper 16 and the walls 15 is kept to a small value except in the corners where clearance is needed to give access to the gas seals. Blocks are bolted to the stopper in the corners. These corner blocks can be removed to provide access to the corner seals shown in Fig. 9. Fig. 3 shows two heat exchangers, 32, 32 in the combination inlet and outlet passages. These heat exchangers open into the combustion chamber 44 at the cylinder end and into valve passages 33, 33 at the valve end. The valve passages 33 and 33 are preferably located in two of the corners of the cylinder, and the admission valves are located on two opposite sides of the stopper 16 and adjacent the valve passages, and the remaining two sides of the stopper 16 adjacent to these same corners are taken up by the exhaust valves. The pipes 42, 42, etc., carry warm, compressed air from the air compressor 26 in Fig. 1 and discharge this warm, compressed air into the low-pressure heat exchangers in the smokestack. The compressed air enters the low-pressure stack heat exchangers at the top of the stack, flows in counterflow relation to the exhaust gases, and emerges from the heat exchangers at the bottom of the stack as shown on Fig. 15. The partially heated air is then carried to the above-mentioned inlet valves, while the outlet valves 75 discharge their somewhat cooled hot gases into

the chimney through corner ducts 130 shown in Fig. 15. The water piston 14 carries a float 40 which follows the water level. The float 40, the walls 15, and the cylinder projection 28 have all the surfaces which line the combustion cylinder protected by heat insulation designated 42, 43, etc., in Fig. 3. The fuel and highly compressed injection air (if any) enters through the fuel pipes 41, 41, 41. The gas seals 100 in the cylinder plug are shown in this figure as at the top of the cylinder walls, whereas in the preferred form shown in Fig. 10, they are in the side of the cylinder walls but still accessible from the valve chambers in the cylinder head 16. The water leaves the cylinder through the arched passageway 28. The arched passageway is completely reinforced throughout and held together against the hydraulic force by the reinforcing. The water leaving through passage 28 has its velocity increased while passing through feeder 21 to the play pipe 22.

Fig. 4 is a cross section plan along the line AA of Fig. 3. It clearly shows the walls 10, 10, etc., that carry the pneumatic and hydraulic pressure developed in the engine from the cylinder walls back to the rock structure 31. This drawing also shows the passages 11, 11, etc., also shown in Fig. 2 which carry the tall water vertically downward to pass into the cylinder basement 14.

Fig. 5 is a cross section in elevation along the lines BB in Fig. 2. One of the vertical walls 10 is shown cast integrally with the horizontal supporting floors 18, 18, 18, 18. These supporting floors are broken into three portions by the extended cracks 38, 38, 38, 38. They form a solid monolithic cast structure with the vertical walls 10, and the whole is cast directly against the rock structure 31. Fig. 5 shows the vertical steel riser plates 60, 60 and the horizontal I-beams 55 are framed into the vertical H-beams 56, 56, 56, etc. (Fig. 5), and the vertical plates 60, 60 which form the grid support of the midsections of the valves and are framed into the horizontal I-beams 55, 55, 55, etc. These vertical supporting plates 60, 60, etc., are stiffened by the stiffeners 53, 53, etc.

Fig. 6 shows the grid arrangement looking in the direction of the arrow M in Fig. 5. Fig. 6 also shows the hinge clips 58, 58, etc., which are welded to the vertical H-beams 56, 56, etc., and the hinged clips 59, 59, etc., which are attached to the valve flaps 17, 17, etc. It is to be understood that these valve flaps may be made of any suitable material, but a preferred form of flap comprises horizontal hardwood planks battened together and covered with a thin veneer of steel.

Fig. 7 is a cross section of the play pipe 22 shown in Fig. 1 taken along the line CC. Fig. 1 shows the main play pipe duct formed by a plurality of flat walls 16, 16, etc.; and at each corner where these flat walls meet there is left a crack opening into a crevice 72, 72, etc., cut out of the rock and forming an opening. The pressure within the play pipe 22 will cause the cracks to extend as at 81, at locations where the pressure is sufficiently high. These cavities 72, 72, etc., are drained by the drain pipes 73, 73, etc., so that it is not possible for hydraulic fluid leaking out of the play pipe 22 to build up high pressure outside of the conduit 22 itself. It is to be understood that this conduit 22 and other similar structures are lined by a thin steel skin; and in the preferred form of the lining, I elect to place small passages at frequent intervals between the lining skin and the concrete which drain into the

drain passages 72, 72, etc., so that leakage (if any) will break out into the passages 72 and will not build up destructive pressures in any part of the rock structure. Fig. 7 shows the cracks sealed by 5 the sealing blocks 14, 14, etc., and it further shows the sealing blocks protected against fluid friction by the thin anti-friction baffles 71, 71, etc., so that the interior of the hydraulic conduit 22 exposes at all points only flat or slightly curved surfaces to the flow of the water. It will be noted that the baffles 71 provide a small auxiliary duct in each corner. It is proposed to block this duct at frequent intervals so that hydraulic fluid will not flow in these small ducts, the flow being confined entirely to the central passage. Frequent small openings will be provided through the baffles 71 so that the pressure on both sides of the baffles will be substantially equal.

Fig. 8 is an enlarged section included in the 20 ring R of Fig. 7. Fig. 8 shows one sealing block 74 in the corner formed by two Z-bars 75, 75. These Z-bars each have one of their flanges forming part of the wall of the drain passage 72. The other flange of the Z-bar is within the cylinder and at frequent intervals has drilled in it holes to accommodate the pipes 76, 76, which are welded in place and form guides for the springs 78, 78. These springs each press a seal block 74 securely into the corner of 25 the passage 22 without regard to the pressure within the duct 22. Fig. 8 also shows the longitudinal stops 88, 88. These stops engage lugs on the seal block which allow the seal blocks to move a very limited amount longitudinally.

Fig. 8A is an enlarged cross section of the 30 sealing key 80 of Fig. 8, as enclosed by the ring marked N in Fig. 8. 82, 82 are keyways carefully cut in the ends of seal blocks 74, 74 so as to exactly match. The key 80 is made to fit in the keyways very closely, and longitudinal stops 88, 88 are welded into the keyways to allow the key 80 only a limited longitudinal motion. This key 80 seals the hydraulic fluid which would otherwise escape out of the conduit through the crack 84 between adjacent sealing blocks 74, 74 and thence directly through the crack at this point between the flat walls of duct 22.

Fig. 9 shows two flat walls 15, 15 of the cylinder chamber 13 in Figs. 1, 2 and 3, and constitutes a gas seal to prevent gases within the cylinder chamber 13 leaking through the cracks where the flat surfaces 15, 15 join. This seal comprises a small passage 86, one corner of which comprises one of the cracks between walls 15, 15 of the cylinder chamber 13. Diagonally opposite this crack is another crack which empties into the drain passage 72. The hydraulic pressure in the small passage 86 is maintained always greater than the gas pressure in the cylinder chamber 13 so that the liquid in the passage 86 will always leak outwards either into the cylinder chamber 13 or the drain passage 72. Seals 74, 74 reduce the flow of liquid out of the passage 86 in the same manner as the seals 74, 74 in the passage 22 of Fig. 7.

The metal structures 88, 84, and 85 constitute the walls of the small passage 86 and are arranged to provide access to the seal blocks 74, 74 as shown. It will be understood that it is necessary to make provision in the projection 28 on the cylinder head 16 as shown in Fig. 3 so that these corners are accessible. This will of course slightly increase the clearance in the cylinder chamber 13, and the amount of this objectionable clearance will be kept to a minimum by filling the corner openings with bolted-in blocks.

Fig. 10 shows a gas seal around the top of cylinder chamber 13 between the rock structure 31 and the cylinder head 16. This is very similar to the structure shown in Fig. 9. In this case the high-pressure passage 100 vents on the outside into the valve chamber 136, 136 (Fig. 15) where leakage must be drained and pumped away and on the inside into the cylinder chamber 13.

Fig. 10A shows an expansion, as for instance P or Q, in the play pipe 22 (Figs. 1 and 2). Steel blocks 122, 122 are welded to the skin 124 of play pipe 22, and the small crack P between these steel blocks is vented to the drain 35. Other small drains as 39, 39, 39, 39, are shown so as to maintain a relatively low pressure back of the steel skin 124, 124 which is secured to the concrete outer steel by the welded-on tacks 123, 123, etc. The flap 36 is mortised into the corner seal blocks as shown diagrammatically at 88, 88, Fig. 8. The seal flap 36 is pressed down by steel springs 37 held in position by steel blocks 38. Steel blocks 38 are welded to the skin 124.

Fig. 11 shows one way to maintain the necessary excess pressure in the gas seals, as for instance 90 in Fig. 9 for the vertical cracks and 100 in Fig. 10 for horizontal cracks. In Fig. 11, 108 represents a motor driving a centrifugal pump 107. This centrifugal pump takes fluid from the fluid piston 14 at the bottom of the cylinder chamber 13 through the pipe 97, increases its pressure, and discharges it into the pipe 98. This fluid which is maintained at a pressure approximately 100 lbs. above the piston pressure is led by pipes 190, 190, etc., into the vertical seal passages 90, 90, etc., and by pipes 109, 109, etc., into the horizontal seal passages 100, 100, etc.

Fig. 12 shows the thermal insulating screen designated 43 in Fig. 3. It is to be understood that this is only one of many available methods of providing a thermal screen to keep cylinder heat away from cylinder walls. In Fig. 12, 110 represents a steel skin on that portion of the cylinder wall which is exposed to gas pressure. This skin 110 is tied into the reinforcing structure 120, 120, etc., buried in the concrete so that the concrete and the skin 110 constitute an integral piece. On this skin 110 are welded a large number of Z-clips 111, 111, 111. Three of these Z-clips are shown in elevation in Fig. 13, and to these Z-clips are welded the screen supports 112, 112, 112. This screen is composed of many shingles 113, 113, etc. These shingles are bent into hooks at their tops by which they are attached to the supporting members 112, 112, etc. In the shingles just below the hooks are the small holes 121, 121, etc., by which it is possible to lash the shingles to the bars 112 by the wire lashings 118, 118, etc.

Fig. 14 shows a shingle 113 of Fig. 12. This shingle is shown having many slots 114, so it is made somewhat in the form of a comb. To this shingle the many small protecting fins F are spot-welded at the spots 119, 119, etc. Between certain of the fins F are wire lashings 116 and 117 by which the individual teeth are attached to the screen supporting members 112, 112, etc. The protecting fins F are bent down after the lashings are in place so that the fins take the larger part of the radiant energy which is thrown against them from the incandescent gases in the cylinder 13. If high-temperature material is available, the fins F will be made of some such metal as "nichrome." If due to a war emergency for instance, this material is not available, a less resistant material must be chosen; and in this case

the ends of the fins may be expected to burn off until the amount of heat carried away by the fins is sufficient to maintain the temperature at an endurable value. It is expected of course that these fins will curl and twist, but they are made very thin (approximately 2 mills) so that they will not greatly distort the comb shingles 113 which are protected against extreme heat by these fins.

Fig. 15 shows the plug 16 of Fig. 1 acting as cylinder head for the cylinder chamber 13. The seals 100, 100 between the plug and the rock structure are served by drains 137, 137, by which leakage out of the seals 100, 100 is drained away to sump pumps. This figure also shows the valve chambers 136, 136, the exhaust gas passages 130, 130, and the chimney 133, and the load of rock and gravel 134. It will be noted that the hot gases enter the chimney 131 at the base and pass out through the enlarged passages 132, 132. The cool compressed air enters the heat exchanger pipes 138, 138 and passes downward to the bottom of the chimney and thence to the intake valves. The intake and exhaust valves are of the usual gas engine construction, and no novelty is claimed for their arrangement or operation. It is proposed to operate them by a compressed air system in which the rise and fall of the piston float 40 cause the operation of the valves at the proper instant of the stroke in a manner well known to the art.

The operation of the entire pump device is as follows: When the water piston float 40 reaches a position several feet away from the bottom of the projection 29 on the cylinder head 16 (Fig. 3), the exhaust valves are closed and the water rushing down in the passages 11, 11, etc., through the high-pressure valves 11, and up the cylinder chamber 13, compresses the exhaust gases in the cylinder chamber 13 to a value closely approaching the pressure of the air as delivered by the compressor 26. Between the compressor 26 and the cylinder chamber 13 is a receiver not shown. This receiver is placed after the heater shown in Fig. 15 so that it contains warm compressed air after it has passed through the air preheater in the chimney. When the piston float 40 is still a number of inches away from the projection 29, the air inlet valves are opened so that as the liquid piston stops and reverses; a flow of warm compressed air is allowed to enter the cylinder through the high-pressure heat exchangers 32, 32. This warm air is greatly heated in the heat exchangers and enters the combustion chamber 44 at a relatively high temperature. The walls of the combustion chamber 44 are initially heated by driving compressed air and gas through a special heat device corresponding to a hot ball in the usual hot-ball oil engine. After the engine has been operated for some minutes, the fire brick, or other lining of the combustion chamber 44, will be incandescent. Gas or oil forced into the combustion chamber 44 through pipes 41, 41, etc., with the highly compressed hot air will burn in the combustion chamber 44 and follow the water piston down in the cylinder chamber 13. When the float 40 has reached a desired position and a small fraction of the down stroke has been covered, the inlet air valves will be closed, and shortly thereafter the fuel will be cut off. The piston will then fall, while the hot gases expand and do their work. When the piston float 40 closely approaches the lowest point of travel, the exhaust valves will be opened, fresh water will rush in from the trailrace 7

through the passages 11, 11, etc., and the valves 17, and the float will rise. The cycle will be continually repeated. It will be noted that the long water conduit 22 will maintain a flow of water to the reservoir formed by the walls 3, 3, nearly, if not all, the time. In other words, if the water conduit 22 is long enough, the low pressure valves 19 will never be called upon to close and the flow of water through the passage-way 2 into lake (Fig. 1) will be continuous and will vary only a minor amount in velocity. It will be noted that the location of the low-pressure valves 19 is such that it will never be possible to develop under the valves 19 a vacuum so great that the water will fall away.

Many changes could be made in the above construction, and many apparently widely different embodiments of this invention could be made without departing from the scope thereof. It is intended that all matter pertaining to the above description, or shown in the accompanying drawings, be interpreted as illustrative and not in a limiting sense.

What is claimed is:

1. An internal combustion engine cylinder located in the ground and comprising a plurality of flat cylinder sides, walls of masonry carrying the pressure on the sides of said cylinder to the earth, and a plug comprising the cylinder head, said cylinder head having a weight greater than the total gas pressure on said cylinder head.

2. An internal combustion engine comprising a cylinder in the earth having a combustion chamber at its upper end, a water piston for said cylinder, a float carried by said water piston in opposition to said combustion chamber, said cylinder comprising bounding walls providing a

5 multiplicity of internal flat surfaces, and a plurality of vertical backing walls of divergent mass between said cylinder walls and the earth, said backing walls supporting and holding said cylinder walls in position.

3. An internal combustion engine cylinder of polygonal cross-section located in the earth, masonry walls of divergent mass between cylinder walls and the earth, said masonry walls being adapted to back said cylinder walls against lateral gas pressure within the cylinder, whereby to transmit to and dissipate said pressure within the surrounding earth.

10 4. An internal combustion engine cylinder located in the ground, the lateral gas pressure in the cylinder wall being supported by the adjacent earth, and a weighty cylinder head mounted on said cylinder which supports the upward pressure of the gas therein.

15 5. An internal combustion engine cylinder located in the ground and having lateral gas pressure in said cylinder supported by the adjacent earth, a weighty cylinder head mounted on the cylinder, said cylinder head supporting the upward gas pressure in the cylinder, a water piston in the cylinder, a float on said water piston, and heat insulation on the cylinder sides and top and on the float.

20 6. An internal combustion engine cylinder located in the earth, the lateral gas pressure in the cylinder wall being supported by the adjacent earth, and a cylinder head mounted on said cylinder which supports the upward pressure of the gas therein, said cylinder head comprising a structure of great weight and strength and being formed to carry a great load of rip rap.

FRAZER W. GAY.
